CLAIM

We claim the ornamental design for lid, as shown and described.

DESCRIPTION

FIG. 1 is a front perspective view of a lid according to an embodiment of the invention. The hub portion and spokes appearing identical in an opposite rear perspective view and on lateral side perspective views.

FIG. 2 is a top plan view of the lid; and,

FIG. 3 is a front elevational view of the lid. The lid appearing the same from the elevational views on the rear side and each lateral side.

The bottom side of the lid is not illustrated and is not part of the claimed invention.

The portions shown in dashed lines are environmental and not part of the claimed invention.
